UNITED STATES PATENT OFFICE.

LEO HAUBERT, OF MUSKOGEE, OKLAHOMA.

TEMPER-SCREW-ADJUSTING DEVICE.

Application filed March 6, 1923. Serial No. 623,135.

To all whom it may concern:

Be it known that I, LEO HAUBERT, a citizen of the United States, residing at Muskogee, in the county of Muskogee and State 5 of Oklahoma, have invented a new and useful Improvement in Temper-Screw-Adjusting Devices, of which the following is a specification.

This invention relates to means for adjusting the temper screws of well drilling machines.

The object is to provide mechanism for this purpose which may be readily installed or incorporated in the structure of the ordinary well drilling machines, such as are used in oil fields, without the necessity for any alteration in the construction thereof, and which will permit of the free and unhampered operation of the same during the 20 drilling process.

Another object is to provide such means which may be readily operated to adjust the said screw, either manually or by the application of power derived from the walking beam drive shaft, such adjustment being readily accomplished during the continued up-and-down movements of said walking beam, and thus avoiding the usual dangerous and laborious process of adjusting the 30 screw by hand, which requires the operator to be elevated to the proper height and to follow the relatively rapid movements of the ordinary adjusting means with his hands and to turn the same while so doing.

A full and complete understanding of the invention may be obtained from a consideration of the following detailed description, taken in connection with the accompanying drawings forming a part of this specification, it being understood that while the drawings show a practical form of the invention, the latter is not to be confined to strict conformity with the showing thereof, but may be changed or modified so long as 45 such changes or modifications mark no material departure from the salient features of the invention, as specifically pointed out in the appended claims.

In the drawings, in which similar reference characters designate corresponding parts throughout the several figures:

Figure 1 is a side elevation of a portion of a well drilling machine having the improved adjusting means applied thereto;

Figure 2 is a similar view of the adjusting means detached from the well drilling machine;

Figure 3 is a plan view of the invention, as shown in Figure 1;

Figure 4 is an enlarged, transverse sectional view, taken on the line 4—4 of Figure 3;

Figure 5 is an enlarged horizontal sectional view, taken on the line 5—5 of Figure 2;

Figure 6 is an enlarged vertical sectional view through the temper screw and the means for elevating or lowering the same;

Figure 7 is a horizontal section taken on the line 7—7 of Figure 6;

Figure 8 is a detail perspective view of the means for mounting the sprocket wheels at the top of the Samson post;

Figure 9 is a detail sectional view taken on the line 9—9 of Fig. 5.

The ordinary construction and arrangement of parts employed in well drilling machines includes a horizontally disposed walking beam 1, mounted at its center on a transverse, horizontal pivot pin 2, suitably seated in center irons or bearing brackets 3, which are secured to the top end of a main post or support 3^a, known as a Samson post. The latter post is suitably braced and reinforced by a supplemental post 4 located in advance thereof and connected thereto by a cross bar 5 arranged near the top of the post 4 which is known as a headache post, the prime function of the same being to arrest the downward movement of that portion of the walking beam 1 located above the same, and prevent injury to the operator or operators beneath, in the event of breakage of the walking beam which sometimes happens at or near the fulcrum of the same.

The end of the walking beam located above the headache post, is equipped for the attachment of the usual temper screw 6, connected at its lower end by a swivel connection 7, to clamping means 8, which firmly grip the cable 9, to the lower end of which are connected the usual drilling tools or other tools used in the drilling of wells.

The opposite end of the walking beam 1 is connected by a pitman 10 to an adjustable wrist pin 11, carried by a crank arm 12, which is mounted on a drive shaft 13. The drive shaft is mounted in suitable bearings

on the upper ends of spaced posts 14, known as jack posts, and the shaft 13 also carries the usual band wheel 15.

As thus far described, the machine is of the ordinary construction generally employed in the drilling of oil and other wells, and these parts require no alteration to permit of the installation of the parts and mechanisms constituting the present invention. proved adjusting means for the temper screw, which is used for the purpose of lengthening the connection between the drilling tools and the walking beam lifting the same, as the said tools drill their way through the earth, such adjustment being limited to the length of the said temper screw. When the temper screw has been lowered or fed out its full length and the cable clamping means is operating close to the surface of the floor, it is then necessary to stop the machine, release said clamps, return the screw and attached clamps to elevated position by the operation of the adjusting means in a reverse direction, when the cable is paid out or lengthened, and the clamps again attached thereto, and the motion of the walking beam may be resumed. As the drills are constantly lowering through their cutting action, it is necessary to intermittently give the screw a slight turning action during the up-and-down motion of the same, in order that the cutting edges of the tools may impact with the bottom of the bore or well, and this turning action has heretofore been done by hand accompanied by great danger to the operator. The device of the present invention is designed to overcome these defects by enabling the operator to effect the desired adjustment or lowering of the tools by a simple turning of a hand wheel to a greater or less degree during the lowering or falling movement of the screw and beam, so that the great weight of the cable and attached tools may not retard such adjustment, or by the simple operation of moving a lever to apply the power of the drive shaft thereto in a direction to feed the screw downwardly step by step, as above described. By a reversal of the movement of the hand wheel, the screw may be elevated as stated, and by moving the said lever in a reverse direction, the power of the drive shaft may be utilized to elevate the screw more rapidly than by hand.

To accomplish these desired results, there is mounted on the drive shaft 13, between the bearing at the upper end of the front jack post 14 and the adjacent face of the band wheel 15, a friction disc 16 divided into halves and clamped to the shaft 13 by bolts 16^a traversing alined ears on the halves, said disc having an annular, outstanding flange 17, preferably flush with the periphery of the same, and an inner annular outstanding flange 18, spaced therefrom. Adapted to

frictionally engage with either one or the other of these flanges, against their opposed faces, is a friction, drive wheel 19, having a facing of leather or other material to enhance its frictional engagement, said wheel 70 being somewhat less in diameter than the space between said flanges, and suitably mounted for rotation, in connection with a sprocket wheel 21, on a stud shaft 20, arranged parallel with and on a horizontal 75 plane with the drive shaft 13, the stud shaft being rotatably mounted in an upstanding rocker arm 24^b, pivoted at its base and adapted to be rocked by a shifting rod 22 arranged longitudinally of the machine. 80

The shifting rod 22 extends slightly beyond the supplemental post 4, and passes through a sliding bearing in the form of a bracket 23 mounted on the rear face of the Samson post 3^a, and through a boxing 24 carried at the end of a bracket 25 which is supported on the post 14.

The bracket 25 is provided with a rearwardly-directed extension 24^a to which the rocker arm 24^b is pivoted at its lower end by 90 a bolt 24^c, as shown in Fig. 9 of the drawings.

At its forward, free end, the shifting rod 22 is pivotally connected to an operating lever 26, arranged, when in a neutral position, vertically and parallel with the post 4, to which the same is pivoted, at its upper end, by means of a short shaft 27 mounted in a bracket 28, bolted or otherwise secured to said post. The handle end of the operating lever 26 is provided with a suitable spring pressed detent for engagement with a notched sector 29, having a centrally located notch 30 which, when engaged by the said detent, maintains the lever in a central or neutral position, at which time the friction drive wheel 19 is neither in engagement with one or the other of the flanges 17 and 18, with the result that the sprocket wheel 21 remains idle. It will be seen that by releasing the detent, and manually moving the lever 26 in one or the other direction, the wheel 19 will be brought into contact with either the adjacent face of the outer flange 17, when the sprocket will be driven in one direction, or in engagement with the adjacent face of the inner flange 18 when a reverse rotation of the wheel will be imparted thereto, the amount of pressure necessary being readily controlled by the hand of the 110 operator.

On the rear side of the Samson post 3^a, as clearly shown in Figure 4 of the drawing, the adjacent end of the pivot pin 2 is retained in its seat in the bearing portion of the center iron 3 by a cap 31, held in position in the usual manner, and having a stud shaft 32 formed integrally therewith, the said stud shaft being in axial alignment with the axis of the pivot pin 2. 125 130

The stud shaft 32 is of a length sufficient to accommodate an inner sprocket wheel 33, an intermediate sprocket wheel 34, and an outer sprocket wheel 35, all of which are 5 loosely mounted on and adapted to revolve independently of the shaft but mounted to rotate together on a sleeve 32^a around the shaft, the said wheels being held upon the shaft 32 by means of a collar 36, pinned 10 or otherwise secured thereto.

The outermost sprocket wheel 35 is connected to the frictionally driven sprocket wheel 21 by a sprocket chain 37, while the intermediate sprocket wheel 34 is connected 15 by a chain 38 to a sprocket wheel 39, loosely mounted for rotation on the extended end of the short shaft 27, to which the aforesaid lever 26 is pivoted, said sprocket wheel 39 being located at the rear side of the 20 post 4 and acting as a hand wheel, to be readily grasped by the hand of the operator, if it is desired to actuate the temper screw 6 by hand power, in a manner to be explained, instead of utilizing the friction 25 drive through the medium of the lever, both actuating means being located adjacent to each other and within easy reach of the operator, who stands adjacent to the rising and falling cable 9 where entering 30 the well.

A sprocket chain 40 passes around the innermost sprocket wheel 33, and extends forwardly towards the temper screw end of the walking beam, said chain having its 35 upper and lower flights passing over flanged idler rollers 41 and 42 respectively, the remainder of said chain extending downwardly and passing around a sprocket wheel 43 mounted on a short shaft 44. The shaft 44, 40 as will be clearly seen by reference to Figure 7 of the drawings, is journalled in opposite bearings 45, formed in the two halves or identical members 46 comprising a hollow casing having outstanding flanges 47, 45 for securing the same, as by bolts 48, to the lower ends of the arms 49, comprising the temper screw frame, which is provided at the upper end with a T-head 50 for connection to the adjacent end of the walking 50 beam.

Between the bearings 45, the shaft is provided with a worm 51 which is in mesh with a worm wheel 52, having threaded connection with the threads of the temper screw, and provided on its upper and lower faces with ball races for the reception of anti-friction balls 53, which are also seated in complementary ball races formed on the inner faces of the top and bottom plates 55 of the casing members, the said casing being composed of two members to facilitate assembling the structure, and the joint between the two being provided with means for preventing leakage of lubricant, with 60 which the casing is designed to be filled.

By the application of either the hand power or the power derived from the shaft 13, it will be seen that the worm wheel 52, which is, in the nature of a nut, may be caused to lift the temper screw upwardly 70 in the frame 49, or by a retrograde movement to allow the same to be lowered. The upper end of the cable 9, while the machine is in operation, is generally held by a hook (not shown) to the bull wheel, which is located adjacent thereto and sufficient slack allowed to permit of the action of the walking beam and to allow the clamp to lower until near the floor level, when said hook is detached, more line paid out to allow the 75 tools to rest on the bottom of the well, the screw is elevated as heretofore described, in the frame 49, after releasing the clamp 8, when the latter is again tightened on the cable at a high point and the operation 80 of drilling begun again.

The upper and lower flights of the chain 40 where extending from the pivot of the walking beam to the outer end thereof, are constantly borne downwardly upon by 85 flanged rollers 54, carried by an arm 55 extending longitudinally of the walking beam on one side, and intermediately pivoted thereto at the central point by a fulcrum pin 56, the opposite end being constantly 90 pressed upwardly by a coiled spring 57 surrounding a guide pin carried by a bracket 58 secured to the side of the beam 1. Thus at all times any slack that may occur in said chain during the up-and-down movement of the walking beam, and due to paying out more cable, is taken care of.

The chain 40 where passing over the idlers 41 and 42, extends substantially parallel to the temper screw 6 so as not to interfere with 105 the rocking movement of the frame 49 about the T-head 50 during the upward and downward movement of the adjacent end of the walking beam.

The upper end of the temper screw 6 is 110 rigidly secured to a cross head 6^a which is adapted to slide up and down between the frame arms 49 and prevent any rotary movement of the temper screw.

In order to secure proper adjustment of 115 the friction roller 19 to place the same half-way between the flanges 17 and 18, when the operating lever 26 is held in neutral position, the shifting rod 22 is provided intermediate its ends, with a turnbuckle 22^a. 120

In the operation of a well rigging including the improved temper screw adjusting means, it is possible to rapidly raise the said temper screw during the operation of the walking beam by means of the power driven portion of the device. This frequently becomes necessary by reason of the caving in of the walls of the well ahead of the drill which prevents the latter from dropping to the bottom, thus causing a slack in the cable 125 130

which must be taken care of by a quick adjustment of the screw in order that the drill may be lifted to again cut its way through the obstruction, and it is also necessary when tools are being fished for, or have become jarred loose, and rise only slightly or not at all, when the beam moves upwardly and the cable has to be taken up accordingly.

From the foregoing, it will be seen that a simple, cheaply manufactured, easily installed means has been provided for use in connection with well drilling machines which may be quickly and safely operated to adjust the temper screw of said machines without the danger usually attendant upon such operations, and that the said screw may be adjusted either by hand power or by the power of the machine driving elements.

What is claimed is:

- 10 20 1. In temper screw adjusting means for well drilling machines having a walking beam and a temper screw connected therewith, a worm wheel having a threaded bore engaging the screw and held from longitudinal movement, a worm in engagement with said worm wheel, a driving sprocket wheel mounted on the shaft of said worm, a chain in engagement with said sprocket wheel, a second sprocket wheel mounted on a fixed 25 part adjacent the walking beam and receiving said sprocket chain, a third sprocket wheel also mounted on said fixed part, a second sprocket chain connected to the third sprocket wheel, and a fourth sprocket wheel 30 around which the second sprocket chain is passed, said fourth sprocket wheel and the second sprocket chain being adapted to be operated manually to rotate the worm wheel and raise and lower the temper screw.
- 40 45 50 55 60 65 2. In temper screw adjusting means for well drilling machines having a walking beam, a temper screw connected therewith, a worm wheel having a threaded engagement with the temper screw and held from longitudinal movement, a transverse worm held in engagement with said worm wheel and having a shaft provided with a sprocket wheel, a second sprocket wheel mounted on a fixed part adjacent the walking beam, a sprocket chain leading from the first sprocket wheel to the second sprocket wheel, a third sprocket wheel also mounted on said fixed part, a drive shaft carrying a disk, means for operating said walking beam from the drive shaft, a stud shaft provided with a sprocket wheel, a second sprocket chain connecting the last mentioned sprocket wheel with the second sprocket wheel, whereby the worm wheel is operated by power from the drive shaft.
3. In temper screw adjusting means for well drilling machines having a walking beam, and a temper screw connected therewith, a worm wheel having a threaded engagement with the screw and held from longitudinal

movement, a transverse shaft carrying a worm in engagement with the worm wheel, a sprocket wheel mounted on said shaft, a plurality of sprocket wheels mounted on a fixed part adjacent to the walking beam spindle, a sprocket chain leading from the first-mentioned sprocket wheel to one of the sprocket wheels on said fixed part, a second chain leading from another one of the sprocket wheels on said fixed part to a manually movable sprocket wheel, and a third sprocket chain leading from the third sprocket wheel on said fixed part to another sprocket wheel, a drive shaft having a driving disc, a drive wheel, and means for mounting the last-mentioned sprocket wheel and said drive wheel so as to engage or disengage the drive wheel with the driving disc and thus actuate the temper screw either by power means or manually.

4. In temper screw adjusting means for well drilling machines having a walking beam, and a temper screw connected therewith, a worm wheel having threaded engagement with said screw and held from longitudinal movement, a worm shaft carrying a worm in engagement with said worm wheel, a sprocket wheel mounted on said worm wheel shaft, a sprocket chain connected to said sprocket wheel, a plurality of sprocket wheels mounted on a fixed part adjacent the walking beam spindle, the said sprocket chain leading from the first-mentioned sprocket wheel being passed around one of said sprocket wheels, manually operated means including a sprocket wheel, a second sprocket chain leading from the last-mentioned sprocket wheel to another one of the sprocket wheels on the fixed part, a drive shaft carrying a driving disk, a shiftable rod, another sprocket wheel mounted to be rocked by the rod, a third chain leading from one of the sprocket wheels on the fixed part to the last-mentioned sprocket wheel, and means provided on the spindle of the latter for engagement with the driving disc so that the driving disc may be caused to operate the temper screw either by power or by hand.

5. In temper screw adjusting means for well drilling machines having a walking beam, and a temper screw connected therewith, a worm wheel having a threaded engagement with the temper screw and held from longitudinal movement, a transverse worm shaft carrying a worm in engagement with said worm wheel, a sprocket wheel mounted on said worm shaft, a drive shaft, means for driving said walking beam from said shaft, a friction disc mounted on the drive shaft and provided with a pair of annular flanges spaced from each other, a shiftable rod having a turnbuckle for longitudinal adjustment, a friction drive wheel mounted to be brought into engagement with

either of the flanges of said friction disc by the shiftable rod, a sprocket wheel mounted to rotate with said friction drive wheel, and sprocket chain gearing leading from the last-
5 mentioned sprocket wheel to and engaging the sprocket wheel on the worm shaft, whereby, by the shifting of said rod, the drive wheel may be brought into engagement with either one of said flanges to rotate the worm
10 wheel and adjust the temper screw up or down.

6. In temper screw adjusting means for well drilling machines having a walking beam, and a temper screw connected therewith, a worm wheel having engagement with the temper screw and held from longitudinal movement, a transverse shaft carrying a worm in engagement with said worm wheel, a sprocket wheel mounted on said
15 worm shaft, a rocker arm, a shiftable rod connected to and adapted to move said rocker arm, a sprocket wheel and a drive element mounted on said rocker arm, a drive shaft, means for operating the walking beam from
20 said drive shaft, a driving disc mounted on said drive shaft and provided with a pair of spaced annular flanges, and means for shifting said rod to bring the drive element on the rocker arm into engagement with
25 either of said flanges, and sprocket gearing leading from the sprocket wheel on the rocker arm to the sprocket wheel on the worm shaft.

7. In temper screw adjusting means for well drilling machines having a walking beam, and a temper screw connected therewith, a worm wheel having threaded engagement with said screw and held from longitudinal movement, a transverse worm
35 shaft carrying a worm in engagement with said worm wheel, a sprocket wheel mounted on said worm shaft, three sprocket wheels mounted on a fixed part adjacent the walking beam, a sprocket chain leading from
40 one of the three sprocket wheels to the sprocket wheel on the worm shaft, a manually operated sprocket wheel, a second sprocket chain leading from a second one of the three sprocket wheels to the manu-
45 ally operated sprocket wheel, a shiftable rod, a rocker arm pivotally connected to said rod, a sprocket wheel and a drive element mounted to rotate in the rocker arm, a third sprocket chain leading from the
50 third one of the three sprocket wheels to the sprocket wheel on the rocker arm, a drive shaft, means for operating said walking beam from the drive shaft, a friction disc carried by the drive shaft and provided
55 with a pair of annular flanges, and means for shifting the said rod to bring the drive wheel into engagement with either one of the flanges of the friction disc whereby said temper screw may be operated either by

power from the friction disc or manually 65 from the manually operated sprocket wheel.

8. In temper screw adjusting means for well drilling machines having a walking beam and a drill-carrying cable connected thereto by a temper screw, a worm wheel 70 having a threaded bore engaging the screw and held from longitudinal movement, a transverse worm held in engagement with said wheel and connected to a worm driving sprocket wheel, a friction disc mounted 75 on the walking beam drive shaft, a shiftable roller mounted to receive forward or backward movement from said disc and carrying a sprocket wheel, a hand-operated sprocket wheel mounted adjacent to the drill cable, friction roller shifting means pivoted adjacent thereto, a plurality of connected sprocket wheels journaled in axial alignment with the walking beam pivot, and chains connecting the connected wheels with 80 the power driven wheel, the hand-driven wheel and the worm driving wheel to impart motion to the latter to adjust the temper screw.

9. In means for adjusting the temper screw in a well drilling machine having a walking beam intermediately pivoted and having a pitman connection with a drive shaft at one end and carrying a temper screw at the other end for connection with the drill cable, a worm wheel constituting a nut in engagement with the temper screw and mounted to rotate at the lower end of the temper screw frame, a housing surrounding the worm wheel, a worm carried 100 by the housing and meshing with the wheel, a sprocket wheel on the shaft of the worm external to the housing, a bearing cap mounted on one side of the walking beam pivot and having a spindle in axial alignment therewith, a plurality of connected sprocket wheels mounted on the spindle and adapted to rotate together, a sprocket chain surrounding a portion of that sprocket wheel next to the beam and having both 105 flights thereof extending toward the cable end of the beam, idler rollers mounted on the side of the latter to support the chain flights in angular course, the latter being in connection with the worm driving sprocket 110 wheel, a chain tightener mounted on the beam and acting on said chain flights between the idlers and the connected sprocket wheels, and operating chains meshing with the remaining connected wheels, one of the latter chains being driven by the walking beam drive shaft and the other by hand power.

In testimony, that I claim the foregoing as my own, I have hereto affixed my signature. 125

LEO HAUBERT.
